UNITED STATES PATENT OFFICE.

GRANVILLE W. WRIGHT, OF NEW HAVEN, CONNECTICUT.

DESIGN FOR A TOY.

SPECIFICATION forming part of Design No. 26,748, dated March 9, 1897.

Application filed July 23, 1896. Serial No. 600,309. Term of patent 3½ years.

To all whom it may concern:

Be it known that I, GRANVILLE W. WRIGHT, a citizen of the United States, residing at New Haven, in the county of New Haven, State of Connecticut, have invented a certain new and original Design for a Toy, of which the following is a specification, reference being had to the accompanying drawings, showing a part thereof.

5 Figure 1 is a side elevation of my design. Fig. 2 is a front or face view of the same, these views being deemed necessary to fully illustrate my design.

10 The leading feature of my design consists of a clown, with a fan in his hand, riding in 15 a two-wheeled cart, same drawn by a horse with harness on and set between the shafts of the cart.

What I claim is—

The design for a toy substantially as herein 20 shown and described.

In testimony whereof I have hereunto affixed my signature this 11th day of July, 1896.

GRANVILLE W. WRIGHT.
